FIG. 6

FIGURE 1 is a side elevational view of a manually operable hand sprayer showing my new design,

FIGURE 2 is a front elevational view thereof,

FIGURE 3 is a top plan view thereof,

FIGURE 4 is a bottom plan view thereof,

FIGURE 5 is a rear elevational view thereof, and,

FIGURE 6 is a perspective view of the sprayer.

The side not shown is substantially the same in appearance as that shown in FIGURE 1. The pump tube is broken away in FIGURES 1, 2, 5 and 6 to show indefinite length.

I claim:

The ornamental design for a manually operable hand sprayer, as shown and described.
